(57) **CLAIM**

The ornamental design for a heat gun attachment for removing caulking, as shown and described.

DESCRIPTION

FIG. 1 is an isometric view of a heat gun attachment for removing caulking;

FIG. 2 is a front view thereof;

FIG. 3 is a rear view thereof;

FIG. 4 is a right hand side view thereof, wherein a left hand side view is a mirror image of the right hand side view;

FIG. 5 is a top view thereof;

FIG. 6 is a bottom view thereof; and,

FIG. 7 is another isometric view thereof shown with environmental subject matter in broken lines.
